UNITED STATES PATENT OFFICE.

JOSEPH P. CLEAL, OF DAYTON, OHIO, ASSIGNOR TO THE NATIONAL CASH REGISTER COMPANY, OF JERSEY CITY, NEW JERSEY, A CORPORATION OF NEW JERSEY.

CASH-REGISTER.

SPECIFICATION forming part of Letters Patent No. 739,649, dated September 22, 1903.

Application filed July 18, 1900. Serial No. 24,076. (No model.)

To all whom it may concern:

Be it known that I, JOSEPH P. CLEAL, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash-registers, and has more particular relation to registers of the multiple or department counter type.

The present invention is an improvement in the type of machine patented to Thomas Carney, No. 497,860, May 23, 1893.

One of the several objects of the invention is to provide a register of the multiple counter type mentioned with a plurality of improved indicators which represent the respective counters and are exposed to view according to the counter operated.

A further object is to provide improved devices for throwing the counters out of operative connection when certain special-trans-action keys—such as the "Paid out," "Received on account," and similar keys—are operated.

In the appended drawings, forming part of this specification, Figure 1 represents a top plan view of the devices embodying my invention applied to a machine of the class mentioned, the cabinet of the same being removed. Fig. 2 represents a vertical section through said devices on the line *x x* of Fig. 1. Fig. 3 represents an enlarged detail perspective view of one portion of the divided-counter shifting-rod and its operating devices for throwing out the counter.

In the said drawings, 1 represents the frame of the machine; 2, the amount-keys; 3, the special keys; 4, the counters; 5, the special push-key, and 6 the special indicators.

As the keys, key-coupler, amount-indicators, counter-operating frames, and connecting parts are substantially of the same construction shown and described in the aforesaid patent, reference is made to the same for a detail description of the parts. In general description, however, it may be stated that the keys are arranged in graduated series or banks and that each of said banks is arranged

to operate a series of vertically-movable indicators and a rocking registering-frame carrying a segmental counter-operating rack. In the said patent but one counter is employed in connection with the said racks; but in my present machine two similar counters are provided and so constructed as to be operated independently and separately by the same key mechanism. The said counters, each 60 of which is similar in construction and operation to that included in the before-mentioned patent, are mounted in pivoted frames 5^a near the opposite sides of the machine, so that they may be adjusted at will to be brought into the 65 proper positions to receive motion from segmental operating-racks 7, 8, and 9 and 10, 11, and 12 or withdrawn from the same. The said racks 10, 11, and 12 receive motion directly from the operating devices substantially as described in said patent, while the racks 7, 8, and 9 are coupled to said first-mentioned racks in a manner hereinafter more fully described.

The oscillating or throwing of the counters 75 into connection with the racks is accomplished by means of cams 13, fast upon the usual rotatable shaft 15 of the machine and engaging, respectively, with antifriction-rollers 16, mounted on the rear ends of throwing-levers 18, which are pivoted on the respective counter-frames. The construction and location of each of these levers are such that the antifriction-roller of the same lies in the path of its respective cam, when the rear end of the 85 lever is allowed to ascend, as hereinafter described.

The levers are operated to raise the antifriction-rollers into the paths of the cams by plungers 20 and 21, mounted in suitable sockets in the frames of the respective counters. Each plunger is forced forward partly out of its respective socket when relieved of the pressure of its arm 22 or 22^a, hereinafter described, by a suitable spring mounted in the 95 socket behind it. (See Fig. 3.) The under sides of the plungers are reduced at different points, as at 23^a, and each of said levers 18 bears with its forward end against the under side of its respective plunger, so that the positions of said plungers, with their reduced portions either in or out of alignment with said

levers, govern the positions of the latter, and thus render them effective or not, as the case may be, the movements of said levers being limited by stop-pins 23, mounted on the frames 5 of the registering mechanisms. The locations of said reduced portions are such that when one of the same is in alinement with its respective lever the other is out of such alinement with its respective lever. The said 10 plungers are arranged to be operated by the arms 22 and 22^a, which are mounted on the respective sections 24 and 25 of a divided slidable rod mounted in suitable brackets in proximity to said counters. The section 25 15 is normally forced toward its companion section by a coil-spring 26, which is interposed between the end of said section and the main frame, said spring being held in position against lateral displacement by suitable studs 20 mounted, respectively, on said rod and frame. Said rod-section 25 is further provided with a locking-arm 27, formed at its outer end with laterally-projecting studs 28 and 29, the former being adapted to enter a suitable socket 25 in its respective counter-frame, and thus lock said frame in inoperative position, and the latter being arranged to enter an aperture formed in a portion of the main frame to lock the said rod against any rocking movement. The 30 arm 22^a is rigidly mounted on this rod-section, so as to abut against the end of its respective plunger 21 to operate the same against the tension of its spring when said rod is moved longitudinally, as hereinafter more fully described. The aforesaid rod-section 24, is like its companion section, normally forced to the right by a coil-spring 30, surrounding the same and bearing with its respective ends 35 against a portion of the main frame, and a collar 31, fast to said rod. This rod-section carries the plunger-operating arm 22, which abuts against the plunger 20 and is provided with a stud-receiving aperture 32 and a locking-stud 33. This stud is arranged to enter a 40 suitable aperture formed in a portion of the main frame to lock the rod against any rocking movement, but at the same time allow it free longitudinal movement. A stud 34, mounted on one of the counter-frames, is arranged to enter the aperture 32, and thus lock 45 said frame and the counter carried thereby in its inoperative position when the rod carrying said arm 22 is moved longitudinally under the impulse of its spring. Both of the 50 rod-sections are moved longitudinally against the tension of their springs through the medium of the special key 5. This key comprises a suitable button or head and a stem 55, which latter is slidably mounted on the main frame and is beveled at its inner end, so as to coöperate with the beveled end of the rod-section 24. The said key-stem is prevented from turning in its supporting-brackets by a suitable slot-and-pin connection with 60 the main frame. This stem is further provided with two collars 36 and 37. The collar 37 forms a stop for one end of a coil-spring 65

38, which surrounds the stem 35, and bears with its opposite end against a portion of the main frame, whereby the special key is normally forced outward into its normal position. 70

For ordinary use of the machine when the respective counters are used for different characters of transactions, such as "Charge" and "Cash," the machine normally registers 75 upon the right-hand or cash counter and only registers upon the charge-counter when the said special key 5 is operated, said key returning automatically to its normal position after the transaction has been recorded. To effect 80 this result, when said special key is forced inward it is temporarily held in this position by a latch-arm 39, which engages the collar 36. This latch-arm is fast to a transverse rock-shaft 40, which is adapted to be rocked 85 upon each operation of the machine by an operating-arm 41, with which it is provided. The weight of the arm 41 is sufficient to hold the latch in its operative position. Said arm 41 is provided at its rear end with an anti-friction-roller 42, which projects into the path of a cam 43, mounted on the rotation shaft 15, so as to be struck and operated by said cam, and thus depress the latch-arm upon each operation of the machine. 95

By the above-described means the special key is released, if it has been previously operated, by the operation of the machine through the amount-keys, and the counters are thus returned to their normal positions 100 after each operation of the machine.

It will be observed from the above description that when the rod-section 24 is forced to the right against the tension of its spring by the inward movement of the key-stem 105 the companion section 25, against which the first-mentioned section abuts, is also similarly moved to the right against the tension of its spring, with the result that the right-hand counter is thrown out of operative condition 110 and the left-hand counter into operative connection. Therefore when the rod-sections move back to their normal positions under the impulses of their springs when the special key is released the conditions of the 115 counters are reversed and the left-hand counter is inoperative and the right-hand counter operative.

When it is desired to include in the machine what is known in the art as the "color system," 120 which system includes the employment of a number of special color-keys, such as 3, for special transactions, the right-hand or cash counter, which is normally in operative condition, is thrown out. When one of the keys 125 3, which represents such transactions as "paid out," "received on account," and "no sale," is operated it is desirable that both counters remain inoperative, so that the amounts may be indicated, but not registered, 130 and to accomplish this result the rod-section 25 must be moved to the right independently of the rod-section 24, which must remain stationary. This is effected by a toggle-lever

44, one end of which is pivoted to the main frame and the other to said rod-section. This toggle-lever is operated by a lever 45, which is mounted upon a transverse rock-shaft 46, which in turn is mounted in the main frame and is provided with a series of cam-edged operating-arms 47. These arms are located under the respective special keys 3, so as to be operated by antifriction-rollers 48, mounted on said keys, when the latter are depressed. By the above-described means the operation of any one of the special keys 3 will operate the toggle-lever, and thus render the normally operative cash-counter inoperative without affecting the charge-counter. This action further renders both of the special indicators invisible, as hereinafter more fully described.

Each of the oscillating counter-frames is provided with a rigid arm 50, having an antifriction-roller 51, which is adapted to engage the periphery of one of two cams 52, mounted on shaft 15, and thus receive motion to return the counter-frame to its original position after the registration has taken place. The aforesaid counter-operating racks 7, 8, and 9 and 10, 11, and 12 for the respective counters are coupled together in pairs in the following manner: The racks 7 and 10, which govern the dollar-registering wheels, are both keyed or otherwise rigidly secured to the shaft 53, upon which they are mounted so as to move together, while the racks 8 and 11, which operate the respective tens-of-cents-registering mechanisms, are loose upon the said shaft, but are yoked together by a frame 54^a, which takes the place of the regular registering-frame and is substantially similar to it. The racks 9 and 12 which govern the five-of-cents-registering mechanism are also mounted loosely upon the said shaft 53 and the said rack 12 is extended to mesh with a pinion 54 fast upon an auxiliary coupling-shaft 55. This shaft is suitably journaled in the frame of the machine and is provided with a second pinion 56, which meshes with the remaining rack 9 of this set. By the above-described means the segmental racks move in sets upon the operation of the keys, so that either of the counters may be operated by being brought into connection with the same. The aforesaid special indicators 6 are two in number, one for each counter, and are pivotally mounted upon a rod 57, mounted above the bank of regular indicators. Each of these special indicators comprises two spaced plates 58, connected by end journal-blocks 59. The two plates of each indicator are provided with similar indicating characters, so that when the said plates are moved to vertical positions an indication will be displayed at both the back and the front of the machine; but when said plates are turned into a horizontal position nothing but the edges of the same will be visible. Each of said indicators is provided at one end with an operating-arm 60, and as the operating devices for these arms are simi-

lar in each instance I will describe one only, as this description will suffice for both. The said arm 60 is pivotally connected to a vertical rod or slide 61, which is suitably mounted in the main frame and is formed with an offset or shoulder 62, which co-operates with the regular indicator latch-bar 63 in order to hold the slide in its elevated position when it is operated. By this construction the special indicator is held in exposed position at the same time as the regular amount-indicators and is only released when the said regular indicators are released. The slide 61 is elevated to bring its indicator into exposed position by a slotted arm 64, which embraces a pin 65, mounted on said slide. This arm 64 is fast to a sleeve 66, journaled on the shaft 55 and provided near its inner end with a shoulder or projection 67, which co-operates with a pin 68, mounted on a lifting-slide 69. The sleeve 66 is connected to the main frame by a coil-spring 70, so as to normally exert a tension to draw the arm 64 down to normal position.

The slide 69 is formed with an elongated slot 71, through which the shaft 55 projects, leaving said slide pendent therefrom. This slide is drawn forward into contact with a rigid arm 72, mounted on the frame of its respective counter by a coil-spring 73, which connects it with the main frame. The lower end of the slide is provided with a shoulder 74, which when the slide is in its normal position is arranged to extend into the opening 75 of the usual key-coupler 76. Should the coupler be elevated when the slide is in this position, the latter will not be operated and the indicator will remain in its unexposed position. Should one of the counter-frames be thrown forward in the manner above described, its arm 72 will rock the slide 69 forward also, so as to bring the shoulder 74 over the key-coupler. As the coupler is now elevated, upon the continued movement of a key the slide is also elevated, and thus brings the indicator to exposed position in the manner aforesaid. As one of the special indicators is brought to exposed position the other is released, as before described, and allowed to return to normal position by the rocking of the bar 63. The characters or words upon the special indicators are made to correspond with the clerk or department for which the respective counters are intended, so that it may be ascertained at a glance just which counter is being employed for any particular transaction. In order to record the number of times each of the aforesaid counters is operated, I provide two special counters 78 and 79. These counters are of the type described and illustrated in the United States patent to Thomas Carney, No. 532,762, dated January 22, 1895, and I will therefore refer to said patent for a detail description of the same. These special counters are operated by means of two oppositely-facing bevel-collars 80 and 81, mounted on the respective rod-sections 24

and 25 and adapted to throw either one or the other of the special counter-operating devices into operative position. Each of these operating devices comprises a pivoted lever 82, 5 an operating - lever 83, pivotally mounted thereon and connected thereto by a coil-spring 84, and an operating-bar 85, fast to the usual key-coupler 76, which is fully illustrated in said patent. This bar is provided with a pin 10 86, which projects into an angular slot 87, formed in the lever 83, whereby when the key-coupler is elevated said pin is depressed and if lying in the upper end of said slot will force the lever 87 downward and operate 15 the special counter connected thereto. The coil-spring 84 normally draws the lever 83 forward out of operative position; but when said lever is forced backward by one of the bevel-sleeves the pin 86 enters the upper portion 20 of the angular slot 87, so that when the bar 85 moves downward the lever 82 will also move correspondingly. It will be seen from the above that when one of the counters is adjusted for operation the operating devices 25 for its respective special counter are also moved to operative position. In addition to the above-described special counters I employ similar counters 88, 89, and 90 for the respective special keys 3. These counters 30 are connected to their respective keys so as to add one unit upon each operation thereof in substantially the same manner as described in the aforesaid Patent No. 532,762. The aforesaid special keys 3 are provided with 35 the usual tablet-indicators, and thus when one of said keys is operated its special indicator is exposed, while both of the counter-indicators are dropped to non-indicating position, as neither counter is thrown forward. 40 If a charge sale is made, the transaction is thrown into the "charge-counter" and the "charge-indicator" raised to indicating position, while if a cash sale is made the companion counter is operated and the cash-indicator exposed. The counters, however, 45 need not necessarily represent cash and credit, as they may be employed for any special transactions, such as "café" and "bar," or for the sales made by different clerks or for sales of 50 different classes of goods.

I have shown my invention as applied to a two-counter machine, which is the preferred form; but it will be readily understood that the invention also includes machines having 55 a greater number of counters.

Having thus described my invention, what I claim as new, and desire to secure by Letters Patent, is—

1. In a cash-register, the combination with 60 a register-operating mechanism, of a plurality of independent registers, devices which are simultaneously shifted to throw one of said registers into and another out of operative connection, means for shifting the said devices and independent means for shifting one of said devices so that no register can be 65 operated.

2. In a cash-register, the combination with a register-operating mechanism, of a plurality of independent registers, a plurality of independent indicators arranged to be controlled by the respective registers, throwing devices for the registers which are simultaneously adjusted to operative or inoperative connection with the register, and means for independently adjusting one of said devices to an inoperative connection. 70

3. In a cash-register, the combination with a register-operating mechanism, of a plurality of independent registers, throwing devices 80 for the registers, and means for simultaneously adjusting said throwing devices, one to an operative and another to an inoperative connection with the registers, a series of special keys, and means arranged to be operated 85 by any one of said keys for independently adjusting one of said throwing devices so that no counter will be operated.

4. In a cash-register, the combination with a register-operating mechanism, of a series of 90 independent registers, and throwing devices, a divided shifting rod for simultaneously adjusting the register-throwing devices, one to an operative connection and another to an inoperative connection with the register, and means for independently moving one portion of the divided rod to independently adjust one throwing device so that no registration will take place. 95

5. In a cash-register, the combination with 100 a register-operating mechanism, of a series of registers, indicators for said registers, means for throwing said registers into connection with the operating mechanism, a series of special keys arranged to adjust the register-105 throwing means out of operative connection with the register, and indicators for such special keys.

6. In a cash-register, the combination with a register-operating mechanism, of a plurality 110 of registers, means for throwing any one of the registers into connection with the operating mechanism, independent indicators, one for each register, and independent means connecting each register to its respective indicator so that when a register is moved to operative position its respective indicator will be 115 likewise set for operation.

7. In a cash-register, the combination with a register-operating mechanism, of a plurality 120 of registers, means for throwing in one of said registers into coöperative relation with the operating mechanism, indicators, one for each register, means connecting said indicators to the registers, for setting the former for operation, and devices independent of the registers for holding the indicators in their exposed positions. 125

8. In a cash-register, the combination with a register-operating mechanism, of a plurality 130 of registers, means for adjusting in one of said registers to operative connection, a plurality of indicators one for each register, independent operating-arms for the respective indica-

tors and means set by the registers for operating said arms.

9. In a cash-register, the combination with a register-operating mechanism, of a plurality of registers and throwing devices, means for simultaneously adjusting said register, throwing devices one to operative connection and another to inoperative connection, a series of special keys for independently adjusting one 10 of said register-throwing devices, and a series of special counters, one for each of said keys.

10. In a cash-register, the combination with a register-operating mechanism, of a plurality of independent registers, and throwing devices, a divided shifting rod arranged to simultaneously adjust said register-throwing devices, a series of special keys, a shaft arranged to be actuated by said keys and means connecting said shaft to one of the rod-sections for moving it independently of the remaining section.

11. In a cash-register, the combination with a register-operating mechanism, of a plurality of independent registers and throwing devices, means for simultaneously adjusting said register-throwing devices to operative or inoperative positions, a series of special keys, a shaft arranged to be operated by said keys, and a toggle-lever adapted to be operated by 25 said shaft to independently adjust one only of said register-throwing devices.

12. In a cash-register, the combination with a register-operating mechanism, of a plurality of independent registers and throwing devices, means for simultaneously adjusting said register-throwing devices to operative or inoperative positions, a plurality of indicators one for each register, a series of special keys having special indicators, and means 35 connected to said special keys for adjusting one of said register-throwing devices alone so that all of said registers may be adjusted to inoperative position and their respective indicators also moved to unexposed position.

13. In a cash-register, the combination with a register-operating mechanism, of a register mounted on a movable frame, an indicator for said register, an arm on said register-frame for setting said indicator for operation, a latch 45 for holding said indicator and means connected to the movable parts of the machine for releasing said indicator independently of the action of the register-frame.

14. In a cash-register, the combination with a register-operating mechanism, of a series of operating-keys having indicators which are arranged in a bank, a plurality of registers arranged to be respectively brought into connection with said mechanism, two independent indicators arranged to extend longitudinally above the bank of regular indicators, and devices connecting the respective registers to said independent indicators.

15. In a cash-register, the combination with a register-operating mechanism, of a plurality of registers and connections, a divided rod for

simultaneously adjusting said register connections, one to operative and one to inoperative connection, a key for moving said rod in one direction, springs for moving said rod 70 in an opposite direction, and means for independently moving one portion of said rod to adjust one connection only.

16. In a cash-register, the combination with a register-operating mechanism, of a series of registers and connections, a divided rod for shifting said register connections, special counters one for each of said registers, and means mounted on the said rod-sections for throwing the special counters into or out of 80 operative condition.

17. In a cash-register, the combination with a register-operating mechanism, of a series of registers and connections, a divided shifting rod, a key for shifting both sections of said 85 rod simultaneously, a series of special keys, a rock-shaft carrying arms arranged to be engaged by said keys, and means connecting said shaft to one of said rod-sections to independently shift the same.

18. In a cash-register, the combination with a register-operating mechanism, of a series of registers, and connections, means for adjusting said register connections to operative positions, a series of indicators, one for each 95 register, and each comprising a pivoted frame having like indicators upon opposite sides, and devices for rocking the frames arranged to be controlled by the respective registers.

19. In a cash-register, the combination with a register-operating mechanism, of a plurality of independent registers and connections, devices for adjusting the register connections so that one of the registers must be operated upon each operation of the machine, and independent adjusting means for throwing out 100 said register connections so that no registration will take place.

20. In a cash-register, the combination with a register-operating mechanism, of a plurality 110 of independent registers, a series of independent indicators for the respective registers, throwing devices arranged to be adjusted so that one of the registers must be operated upon each operation of the machine, and independent adjusting means for throwing out 115 said throwing devices so that no registration will take place.

21. In a cash-register, the combination with a register-operating mechanism, of a plurality 120 of registers, independent indicators for the respective registers, and independent means controlled by the registers and arranged to set the respective indicators for operation when the registers are moved into connection 125 with the operating mechanism.

22. In a cash-register, the combination with a register-operating mechanism, of a plurality of registers, independent indicators for the respective registers, indicator-operating devices arranged to be set by the said registers, a series of operating-keys and a member com-

mon to all of said keys and arranged to actuate the indicator-operating devices when the latter are set for operation.

23. In a cash-register, the combination with 5 a register-operating mechanism, of a plurality of registers and connections, means for adjusting any one of said register connections for coöperation with the operating mechanism, and a series of special keys arranged to 10 adjust one of said register connections independently of another.

24. In a cash-register, the combination with a register-operating mechanism, of a plurality of registers, shifting devices arranged to be 15 adjusted simultaneously, a series of special keys, a rock-shaft carrying arms arranged to be engaged by said keys, and means connected to said shaft and arranged to adjust one of said shifting devices independently of another 20 so that no registration will take place.

25. In a cash-register, the combination with a register-operating mechanism, of a series of registers, a divided mechanism the parts of which are arranged to be adjusted simultaneously, a series of special keys, a rock-shaft carrying arms arranged to be engaged by said keys, and means connected to said shaft for independently shifting one portion of the divided mechanism so that no registration will 30 take place.

26. In a cash-register, the combination with a special key, of independent indicators, independent operating devices controlled by said key, operating mechanism and independent means arranged to be set for operation by said independent operating devices and connected to the respective indicators.

27. In a cash-register, the combination with a register-operating mechanism, of a plurality of independent registers arranged so that one of them is normally in operative condition, special indicators for said registers, and means for destroying this normal condition so that the registers will not receive a registration upon the operation of the machine.

28. In a cash-register, the combination with a register-operating mechanism, of a plurality of independent registers arranged so that one of them is normally in operative condition, 50 special counters one for each of the independent registers, and means for destroying the normal condition of the independent registers so that neither of said registers will receive a registration upon the operation of the 55 machine.

29. In a cash-register, the combination with a register-operating mechanism, of a plurality

of independent registers, throwing means arranged so that one of the registers is normally in operative connection, and means independent of the throwing means for destroying this normal condition so that there will be no registration upon the operation of the machine.

30. In a cash-register, the combination with 60 a register-operating mechanism, of a plurality of independent registers, throwing means arranged so that one of the registers is normally in operative connection, a series of special-transaction keys, and means operated 70 by said keys and arranged to destroy the normal condition of the throwing means so that there will be no registration upon the operation of the machine.

31. In a cash-register, the combination with 75 a register-operating mechanism, of a plurality of independent registers throwing means arranged so that one of the registers is normally in operative connection, a series of special-transaction keys, a rock-shaft operated by said keys, and means operated by 80 said shaft and arranged to destroy the normal condition of the registers so that there will be no registration upon the operation of the machine.

32. In a cash-register, the combination with a register-operating mechanism, of a plurality of independent registers, indicators for said registers, slides for operating said indicators, a movable member and means mounted on 90 the registers for throwing their respective slides into coöperative relation with the movable member.

33. In a cash-register, the combination with an operating mechanism, of a register mounted 95 in a movable frame, a special indicator, a movable member actuated by the operating mechanism, and an indicator-operating device moyed by the register-frame into the path of the movable member.

34. In a cash-register, the combination with an operating mechanism, of a plurality of registers mounted in movable frames, a special register-indicator, and an operating device for said indicator constructed to be set 105 by one of the register-frames for movement in connection with the operating mechanism.

In testimony whereof I affix my signature in the presence of two witnesses.

JOSEPH P. CLEAL.
